(57) **CLAIM**

The ornamental design for a mounting wrench for a garbage disposal, as shown and described.

DESCRIPTION

FIG. 1 is a top perspective view of my design for a mounting wrench for a garbage disposal;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a rear view thereof; and,

FIG. 8 is an exploded top plan view thereof.

The broken lines shown on the drawings is included for the purpose of illustration and forms no part of the claimed design.
